FIG. 8.

FIG. 9.

UNITED STATES PATENT OFFICE.

DAVID C. KLAUSMEYER, OF CINCINNATI, OHIO, ASSIGNOR TO THE CINCINNATI BICK-FORD TOOL COMPANY, OF CINCINNATI, OHIO, A CORPORATION OF OHIO.

ADJUSTABLE WORK SUPPORT.

Application filed May 20, 1921. Serial No. 471,074.

To all whom it may concern:

Be it known that I, DAVID C. KLAUSMEYER, a citizen of the United States, and residing at 3638 Burch Ave., Hyde Park, Cincinnati, in the county of Hamilton and State of Ohio, have invented a new and Improved Adjustable Work Support, of which the following specification is a full disclosure.

This invention is directed to those structural features in machine-tools whereby the various relations between the tool and the work, necessitated by the character of the tooling-operation, may be obtained easily and maintained rigidly and, while this invention is applicable to various types of machines, its utilities and advantages are more highly developed in its application to drilling machines embodying a radial arm employed for supporting the work.

In drilling machines of various types it is usual to provide a work or tool support which is adjustable vertically with respect to a supporting column and further means are provided adjacent the column to raise and lower the work-support and to clamp it in its various adjusted positions. Means are also habitually provided adjacent the column to adjust the work table laterally relative to the tool and to clamp it in its adjusted position, or to swing it out of the way and support the work on the floor of the bed from which the column rises.

The column (which specifically may be either a non-rotatable post about which the arm may swing, or an upright rotatable sleeve from which the arm radiates) habitually supports one end only of the arm that carries either the work-support or the drill-head, as the case may be. This arrangement possesses the mechanical defect of being more or less resilient and, although in many respects convenient, it is not entirely so; since the user cannot clamp the arm without leaving the position from which he can best examine the adjustment of the tool to the work.

In the simpler types of drills, it is customary to elevate the arm and the table by hand and, for this and other reasons, it is desirable to make the parts as light as accuracy, rigidity and quality of materials will permit. Likewise it is desirable so to fashion the arm that it may easily be made through ordinary foundry methods and so

to mount it that it may at all times be rigidly resistent to the working pressures. Heretofore, all this has been achieved in an entirely satisfactory manner; the necessity of providing for universality in the table adjustments having introduced difficulties.

In its preferred form, this invention proposes a box-like arm rigidly supported from the floor table-like, so to speak, at its four corners so as to brace it positively against either bending down or rocking sidewise, and so as to relieve the column of any untoward deflection streams, and to achieve this result without interfering with the facility with which it may either be elevated or swung around the column.

It is a further object of this invention to provide an arrangement whereby the operator, while stationed in his usual position in front of the work-table, may conveniently effect the locking to the supporting-column of the supporting arm of the work-table.

A further object of the invention is to provide an arrangement whereby the entire control of the adjusting of the table (both clamping and raising) may be effected by the operator without moving from his regular working-position.

This invention also aims to provide a novel, simple and easily adjusted means for supporting the outer end of the arm, in all of the various positions it may occupy, so as to preclude any undue deflection of the arm and so as to prevent any undue strains, caused by the pressures of the drilling operations, from being transmitted to the column or unduly straining the same.

Also, it proposes an improvement in the manner of clamping the column and table to the arm, whereby there will occur no inaccuracies in the seating of the elements due to the movement or deflection of the clamping wings or parts.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part

of this disclosure and, in such drawings, like characters of reference denote corresponding parts throughout all the views, of which:—

Fig. 1 is a side elevation of a fragmentary portion of a machine tool embodying my novel clamping, table-adjusting and arm supporting mechanics. Fig. 2 is a section on the line 2—2 of Fig. 1. Fig. 3 is a view similar to Fig. 1 but looking at the opposite side of the machine tool. Fig. 4 is a top plan view of my work-table together with its supporting arm. Fig. 5 is a front view of a fragmentary portion of machine tool. Fig. 6 is a section along the line 6—6 of Fig. 3. Fig. 7 is a view similar to Fig. 3 showing a modified form of my invention. Figs. 8 and 9 show the use of rollers at the feet of the supporting leg.

In the several views, A indicates base in the nature of a bed-plate to which is rigidly secured (by bolts 5 passing through the flange 4) a vertical supporting column B upon which is vertically and pivotally adjustable a horizontal supporting arm C. This column may, of course, be formed in any conventional manner such as box-type or cylindrical in form and it may assume the form of a rotatable sleeve or may, as shown, be in the nature of a rigid post about which the arm may turn. The bed C is formed to present plane surface 1 adapted to serve the two-fold office of a platform on which certain bulky pieces of work may be placed, and so as to present a smooth uniform surface on which feet of the arm-supporting legs may rest and on which such feet may also freely slide in an arcuate path without interference when the arm is being swung into its various positions of adjustment, as will be presently explained.

For the purpose of collecting surplus oil and chips, the base may have a moat 3 leading to a collection well 2 in the usual manner. The arm C is comprised preferably of a semi-circular portion C' in the nature of one half a split sleeve and an arm proper in the nature of a box-like structure or body portion having two spaced walls 9 and 10 suitably reinforced on their interior surfaces by ribs 11 and 12 extending transversely to increase the strength of the walls without adding undue weight to them. As will be seen from Fig. 2, these ribs run cross-wise and terminate short of the hollow central region of the arm; making it a simple matter to cast said arm. It is to be noted that the joints, between the cap and arm proper, are in a transverse, instead of longitudinal, plane for a reason hereinafter appearing. The side walls 9 and 10 (see Fig. 6) converge forwardly and are tapered vertically and, at each end, they are merged integrally into rigid bearing portions for the column and the hub of the table, respectively, in a manner ensuring absolute accuracy in the align-

ment of these elements. Thus, the semi-circular sleeve 21 provides upper and lower semi-annular bearings *a* and *e* (see Fig. 1) which determine the seating of the box-like arm on the column irrespective of the clamping movement of the clamping cap C'; this sleeve being cast integrally with the arm and preferably being open at 20 in the interest of lightness.

The clamping-cap C' is, at one side only, firmly affixed to the arm C; this being effected by means of the bolts 45 binding together the lugs *w* and *s*.

The clamping cap C' is, on its other side, provided with ears *m*, *o* and *s* adapted to cooperate with ears *n* and *r* on one side of the wall 20 and an ear *w* on the other side of the wall or sleeve 20 respectively. Bolts 32 and 33 pass freely and loosely thru the ears *m* and *r*, and are tapped into the ear *n* and *o*; the arrangement being preferably made in a converse manner, as shown by Fig. 1. The bolts 32 and 33 do not bind the clamping cap to the arm but afford sufficient free-play to allow for a clamping and un-

clamping action. In order to use the cap C' for the purpose of pulling the seats *a* and *e* truly against the column B and also for effecting the clamping, a shaft T is provided; said shaft being threaded into the lug *m* and being provided with a collar 34 so that, when it is rotated, the collar will pull the cap and arm together thereby clamping the socket against the column. Inasmuch as the weight of the arm will normally operate to press the lower seat *e* against the column and will tend to pull the upper seat *a* away from the column, the clamping shaft will preferably be located at the upper portion of the arm; preferably, as shown, somewhat above the seat *a* to obtain the benefit of as much leverage as possible and relieve the threads of the shaft T of unnecessary duty.

In order to render the clamp-actuating shaft accessible to the operator without obliging him to move from his normal operating position in front of the table, and to achieve this in a structurally simple manner, the clamping split has been located at a side of the arm and the shaft is prolonged or otherwise extended to the vicinity of the table which occupies a position more or less remote from the supporting column. To that end, it may pass thru a bearing 17 on the forward part of the arm and be provided with a squared end U adapted to be connected with an operating handle. By this arrangement, or its equivalent, the user can make the most delicate adjustment in elevation between the drill and the work and clamp the table in place with certainty.

To raise and lower the supporting arm, when the clamping mechanism just described is loosened an upright rack L is arranged ad-

5 jacent the column. This rack has its foot 44 resting on an annular ledge 6 provided by the column; this ledge serving as a rail around which the rack may glide as it travels around the column. The inner face 43 of the rack is concaved slightly so as to bear evenly on the periphery of the column and the rack is contained in a suitable recess in the nature of a spline groove within the 10 bore of the two-part sleeve of the arm, as shown by Figs. 4 and 2. By removing the C', the rack may be removed and, in normal use, it is held upright and close to the column by said spline groove. A pinion M 15 meshes with said rack, said pinion being mounted in a bearing 38 in the boss N split at 39 and integral with the arm C and cap C'. The protruding end of the shaft of the pinion is provided with a worm gear O 20 adapted to mesh with a worm P mounted in a first bearing 42 within the chamber of a boss 40 cast integral with the arm C and in a second bearing in a cover plate 41 suitably secured to the boss for the worm. The exposed end of worm shaft is provided with a squared portion Q whereby it may be turned manually, as by means of a suitable handle. While, in this arrangement, the elevation of 25 the table effected from a position at the side of the column, its lateral adjustment is completely within the control of the user while stationed adjacent the table. It is the lateral adjustment that must be made with the greater nicety for the reason that the precision of location of the hole to be drilled by a 30 vertical drill is dependent thereupon, as will be understood. The arm, being arranged to swing about a vertical axis (which in the example illustrated coincides with the axis of the column), may easily be shifted laterally when unclamped; being still supported by the elevating mechanism which, in this instance embodies the rack that then serves as a travelling supporting leg, so to speak. 35 The frictional resistance to this adjustment at the bearing points 30 and e may be appreciably diminished by the proper use of the travelling means for supporting the outer end of the arm, to be presently described. 40 So also, this invention affords a compound adjustment in a horizontal plane by combining a table with the arm in such a manner that it may be adjusted relatively thereto and clamped in place also from the front of the machine, as will be explained. 45

50 In Fig. 7, there is shown a modification wherein the elevating as well as the clamping controls are within reach of the operator when he is directly adjacent the table. In 55 this instance, the elevating rack-and-pinion mechanism is arranged in the longitudinal plane of the arm; thereby locating the rack in the thrust-plane of the arm, instead of at the side of such plane. This has the two-fold advantages of giving a convenient direc-

tion to the worm shaft and also of somewhat easing the pressure (and consequently the friction) on the thrust bearing 30 and thereby reducing the labor of moving the arm. By locating the pinion near the thrust bearing 30, the thrust, caused by the pressure-angle of the rack teeth, will be exerted in a direction contrary to the thrust against the bearing 30 due to the weight of the arm and, by increasing the pressure angle of the teeth, the friction may to a corresponding extent be diminished. 70

In the illustrated modification, the pinion is located adjacent the rear bearing 30; the clamping cap C'' being provided with a 80 housing k on its rear side within which said pinion is located in engagement with said rack.

The worm wheel x is located at the side of the cap so as to be in mesh with the worm z which is secured to the rear end of a shaft Z extending forwardly alongside the arm and terminating in an operating end located adjacent the working station of the user; thereby affording a control of both the elevating and clamping means from the front of the machine. 85

When it is desired to change the level of the work-table, the clamping shaft T is rotated to release the clamp; the separation of the portions of the socket being limited by an abutment of the ears with the bolts 32 and 33. Because of the self-locking character of a worm drive, the work table is prevented from dropping, even when the clamp has been loosened. The shaft P or Z, as the case may be, is then operated to raise or lower the table. After the table has been adjusted to its desired height, the arm is clamped on to the column B by means of the shaft T. 90 Ordinarily, the vertical adjustment does not have to be made with the exactness of the lateral adjustment so long as the drill is arranged to feed in a vertical direction, i. e., in the same direction as the work is adjusted, 105 since in that event its primary object is merely to bring the work comparatively close to the drill-point so that the drill, within the limits of its feed, may penetrate the work to the desired depth. 110

The means for obtaining a fully universal lateral adjustment for the work, either towards or away from the column or to one side or the other of the drill (which is suitably supported from the upper portion 7 of 120 the column, as by a member secured thereto through the guides 8) will involve a cooperating member in the nature of a work-support adjustably mounted on the arm so as to have an independent movement thereon. 125 This member may, very conveniently, be pivoted to the arm and may assume the form of a circular table D having a hub F journaled in a vertical socket in the end of the arm. It is very important, in the interests 130

of precision, that the surface of the table should at all times coincide exactly with a plane at right angles to the axis of the column; this axis being likewise the determinant of the axis of the drill whenever it is desired, as is usually the case, to drill a hole in the work at right angles to the surface of the table. It is important, also, to enable the hub to be very firmly locked in its angular position in said socket.

Heretofore, this clamping has been effected by a continuous split in the wall of the socket with the result that the seating of the table on the arm was more or less perturbed by reason of the slight movement of the well segments necessary for their clamping function. This error is, however, eliminated by the construction herein proposed which provides a seat all effective portions of which are rigid with the arm and are in no manner subject to deflection with respect to the arm; irrespective of the action of the clamping agent. As shown by Figs. 3 and 4, the arm extends integrally, on its upper end-portion, in the form of an annular plate or ring 13 which is free from any splits and which provides an upper annular surface 14 in the nature of a rigid seat upon which rests the under bearing surface of the table which is thereby given a true and solid support independently of the clamp. The clamp consists of two arcuate wings 23 and 24 (see Fig. 2) formed in the lower wall-portion of the socket by the arcuate split 15 (see Fig. 7) which separates the wings from the solid seat 13 and by the cut 16 in an axial plane which gives the wings the degree of resilient movement required for the clamping action. Lugs 19 are cast at the free edges of these wings and a suitable draw bolt G, actuated by a handle G', enables the user, when in his working station, to operate this clamp and with precision determine the lateral relation, in a truly universal sense by reason of the equally accessible arm-clamp, of the drill to the work.

The ease with which this adjustment may be effected, even when a heavy piece of work is carried by the table, and the rigidity with which the work may be supported against the pressures of the drilling operation, results from a further improvement in the nature of a vertically-adjustable and laterally-shiftable arm-support HJ arranged to ride on the track-like surface I presented by the bed. This surface I, although essentially in the nature of an arcuate guide-way or track for the foot or feet, as the case may be, of the arm-support, is preferably made flush and continuous with the surface of the bed so that it will not interfere with the use of the bed when it is desirable to bolt large heavy objects thereto. This arm-support HJ is a two-part device; its one part

H being a component part of the arm and its other part J being an independent leg adjustable with relation to the arm in conformity with the elevation thereof arbitrarily selected by the attendant. The support J may be a one-piece element preferably consisting of legs t and f spaced apart to give a wide base of support and thereby brace the arm most effectively against any twist under the pressure of the drill. These legs t and f are preferably connected by a web and the whole may be regarded as a single leg the width of which may be increased or decreased in accordance with the extent to which special refinements of this invention are utilized. When the highly desirable wide base is resorted to, the legs t and f may be extended upwardly to seat on the clamping surfaces presented by the two depending guides H and H' (see Fig. 5) the clamping portions 27 of which are slotted to permit the passage of the clamping bolts 36. These slots are of such length that when the bolts 36 reach the upper ends 35 of the slots the under surface 22 of the arm will approximately reach the annular track 6 on the column; thereby affording a full range of movement. These depending guides H and H' are preferably integrally connected by means of cross-rod 22 and 26 and, at their upper ends, they are secured by bolts 28 to lugs 17 extending from the arm, independently of the flexible clamping wings 23 and 24, so as to be rigid with the seat 14 on which the turn table rests; thereby transmitting the supporting thrusts directly to the table and securing the great solidity and rigidity so desirable for tooling operations. It is noteworthy that the adjustment of the table-support may also be readily effected from the working-station of the user. The legs H and H' in connection with the column B (or the rack L) constitute a species of travelling tripod for the arm by reason of the slideable relation between the feet of the legs and the arcuate guide-way L; thereby producing a structure entirely compatible with all of the adjustments, both lateral and vertical; while yet serving effectively to brace the arm against deflection. As shown by Figs. 8 and 9, the feet of the legs are provided with rollers N¹ and N² which are preferably set at an angle so as to be tangential to the arc of swing. These rollers, in combination with the other above-described elements have been found in practice to greatly facilitate the manipulation of the table inasmuch as they ride very easily on their arcuate track and support the weight of the table equally well in all of its positions of adjustment.

Without further analysis, the foregoing will so fully reveal the gist of this invention that others can, by applying current knowledge, readily adapt it for various uti-

lizations by retaining one or more of the essential characteristics of either the generic or specific aspects of this invention, and, therefore, such adaptations should be, and are intended to be, comprehended within the meaning and range of equivalency of the following claims:—

Having thus revealed this invention, I claim as new and desire to secure the following combinations and elements, or equivalents thereof, by Letters Patent of the United States:—

1. A machine-tool combining an arm having its free end apertured and provided with a continuous annular bearing, a portion of the sleeve surrounding said aperture being split circumferentially to separate it from said continuous bearing portion, said sleeve being also split transversely to said circumferential split to provide resilient clamping wings; a rotatable table having a hub within said continuous bearing on said split portion; and means on said sleeve for deflecting said wings to clamp said hub firmly to said arm.

2. A machine-tool combining an arm terminating in an apertured end having a rigid continuous annular seat circumscribing one end of said aperture, said arm also providing arc-shaped wings constituting flexible wall portions of said aperture; a work-support resting on said rigid seat and having a stem within said aperture; and means for flexing said wings to clamp said stem against movement.

3. A machine-tool combining an arm terminating in an apertured end having a rigid continuous wall providing an annular seat circumscribing one end of said aperture, said arm also providing arc-shaped wings constituting flexible wall portions of said aperture; a work-support resting on said rigid seat and having a stem within said aperture; means for flexing said wings to clamp said stem against movement; and a supporting-leg having a portion connected with said rigid wall.

4. A machine-tool combining a base; a column rising therefrom; an arm mounted to rotate about, and slide vertically on, said column, and extending normally thereto; a work-support mounted on the free end of said arm; mechanism for elevating said arm; a clamp to secure said arm in adjusted elevation and rotative position; and means operable from a station adjacent to said work-support at the free end portion of said arm for enabling it to be clamped by a single operation against sliding and rotation.

5. A machine-tool combining a work-table and a supporting-arm therefor; a supporting-column upon which said arm is mounted to rotate horizontally and to slide vertically; and clamping-mechanism to secure the arm to the column in adjusted elevation and ro-

tative relationship, by a single operation, said mechanism comprising an operating element extending adjacent to the edge of the work-table remote from the supporting column.

6. A machine-tool combining a work-table and a supporting-arm therefor; a supporting-column for said arm, clamping mechanism to secure the arm to the supporting-column comprising a unitary cap joined to said arm in a plane substantially at right angles to a plane passing thru the work-table and column; and means threaded thru said joined portions to bind the portions together, said means extending adjacent to the edge of the work-table remote from the supporting column.

7. A machine-tool combining a supporting-column; a supporting-arm adjustable horizontally and vertically on said column; means for clamping the arm to the column in adjusted vertical and horizontal position by a single operation; a work-table adjustably secured to the arm; means for clamping the work-table to the arm; and operating-mechanism for both said clamping mechanisms arranged adjacent to the edge of said work-table remote from the column.

8. A machine-tool combining a work-table and a supporting-arm therefor; a supporting-column for said arm; clamping-mechanism to secure the arm to the supporting-column, comprising a unitary cap joined to said arm in a plane substantially at right angles to a plane passing thru the work-table and column; a rack and pinion confined within said joint at one side of said column, for elevation of said arm thereon; and means threaded thru said arm and cap at the opposite side of said column, to bind the joined portions together, said means extending adjacent to the edge of the work-table remote from the supporting-column.

9. A machine-tool combining a work-table and a supporting-arm therefor; a supporting-column for said arm; clamping-mechanism to secure the arm to the supporting-column, comprising a unitary cap joined to said arm in a plane substantially at right angles to a plane passing thru the work-table and column; a rack and pinion confined within said joint at one side of said column, for elevation of said arm thereon; and means threaded thru said arm and cap at the opposite side of said column, to bind the joined portions together, said means extending adjacent to the edge of the work-table remote from the supporting-column; and means on both sides of said joint to hold said arm and cap, with said rack and pinion, in assembled relation upon said column, independently of said binding-means.

10. A machine-tool combining a vertical supporting-column; a horizontal arm adjustable vertically and horizontally on said

- column; a work-table secured to said arm; means for securing the arm to said column comprising a two-part socket embracing the column; cooperating ears on the two diametrically opposite portions of the socket; bolts loosely holding the parts together; and a clamping shaft passing thru one ear and having its projecting end threaded into the cooperating ear; a shoulder on said shaft adapted to bear on said first ear, said shaft being operative to bind the parts of the socket together upon a rotation thereof; said shaft extending forward along one side of said arm and terminating at the outermost end of said arm in an operating extremity, to permit manual actuation thereof from a station adjacent to said work-support, to clamp said arm in adjusted vertical and horizontal position on said column by a single operation.
11. A drilling-machine combining a column; an arm slideable vertically on said column and rotatable transversely thereto; clamping means for restraining said movements; a base supporting said column and providing an arcuate guide-way underlying the free end of said arm and a strut adjustably depending from the free end of said arm, having contact with said arcuate guideway at points spaced apart a distance

not materially less than the thickness of the column; and a work-support carried by said arm.

12. A drilling-machine combining a column; an arm slideable vertically on said column and rotatable transversely thereto; clamping means for restraining said movements; a base supporting said column and providing an arcuate guide-way underlying the free end of said arm; a strut adjustably depending from the free end of said arm having contact with said arcuate guide-way at points spaced apart a distance not materially less than the thickness of the column; clamping means to secure said strut in adjusted elevation; and a work-support carried by the arm and adjustable in a horizontal plane thereon; and clamping means for locking said work-support against movement relative to said arm; each of said clamping means being arranged to be manually operated from a station adjacent to said work-support.

In witness whereof, I hereunto subscribe my name, as attested by the two subscribing witnesses.

DAVID C. KLAUSMEYER.
